US0D1082219S

(12) United States Design Patent (10) Patent No.: US D1,082,219 S
(45) Date of Patent: * Jul. 8, 2025

(54) PANTS

(71) Applicant: Swiss Intellectual Properties & Licensing AG, Wilen b. Wollerau (CH)

(72) Inventor: Sabrina Salvadori, Wilen b. Wollerau (CH)

() Term: 15 Years

(21) Appl. No.: 35/520,428

(22) Filed: Feb. 19, 2024

(80) Hague Agreement Data

Int. Filing Date: Feb. 19, 2024

Int. Reg. No.: DM/235978

Int. Reg. Date: Feb. 19, 2024

Int. Reg. Pub. Date: Mar. 29, 2024

(51) LOC (15) Cl. 02-02

(52) U.S. Cl.

USPC D2/731

(58) Field of Classification Search

USPC D2/731, 728, 717, 742

CPC A41D 31/18; A41D 13/0015
